Application August 16, 1950, Serial No. 179,672

8 Claims. (Cl. 242—19)

1

This invention relates to an improved tail cutter for winding machines and it is especially adapted for use with a winding machine of a type known as the Whiting-Schweitzer automatic filling bobbin winder, manufactured by Whiting Machine Works of Whitinsville, Mass.

Heretofore machines of the type described have been equipped with a tail cutter comprising a substantially pointed member having a knife edge which automatically passes adjacent or between the rings on the base of a bobbin for severing the tail of yarn upon a bobbin being filled and prior to its being ejected and an empty bobbin replacing the same. However, it has been found that sometimes the point of the cutting blade will engage the base or wooden part of the bobbin adjacent or between the rings and would thus damage the periphery of the bobbin.

Moreover, the rings of the bobbin are not complete rings but are split and thus there is a gap at each ring through which the yarn tail may pass. When the tail passed through the gap of the ring adjacent the blade of the prior art cutter, it would not be raised sufficiently from the surface of the bobbin to be engaged and cut by the blade.

It is an object of this invention to overcome such defects by providing an improved tail cutter including a blade member which is normally spaced substantially radially of the rings on the base of the bobbin during a winding operation and, upon completion of the winding operation, said member, which is provided with a plurality of projections thereon, is adapted to be projected into operating position, in which position the projections will be disposed within the spaces between the rings on the base of the bobbin and will engage the yarn at one or more points where it crosses the rings, with rotation of the bobbin, so as to sever or break the tail of the yarn. Since the projections which penetrate between the rings on the bobbin have a total length which is less than the depth of the spaces defined by the rings, it is impossible for the projections entering between the rings on the bobbin base, to engage the wooden base of the bobbin and to damage the same.

More specifically, it is an object of this invention to provide, in a winding machine of the type described, a tail cutter blade adapted to be moved into operative position in a radial plane relative to the axis of a bobbin in which filling is being wound, the blade being provided with a plurality of notches in one edge which coincide with the rings on the base of the bobbin and

2

which define a plurality of projections preferably of less length than the depth of the spaces defined by the rings and means for supporting the blade including a tail cutter blade support member pivotally supported on the machine on an axis parallel to the axis of the bobbin on which the filling is being wound and including means automatically operable upon a bobbin being filled for swinging the support member and its cutter blade into operative position, there being suitable stop means for accurately determining the position at which the blade will stop adjacent the base of the bobbin so the projections on the blade will extend past the peripheries of the rings on the base of the bobbin and will terminate in closely spaced relation to the periphery of the base of the bobbin without engaging the same, but close enough to the bobbin that the space between the projections and the base will be less than the diameter of the yarn.

It is another object of the invention to provide a tail cutter of the type described with spring means interposed between the tail cutter blade support member and the means for actuating movement of said member so as to permit the said actuating means to continue its movement after the blade on the blade support member has moved to the desired position in closely spaced relation to the base of the bobbin and whereby the actuating means for the tail cutter blade support member need not be precise as to its length of stroke.

Some of the objects of the invention having been stated, other objects will appear as the description proceeds when taken in connection with the accompanying drawings, in which—

Figure 1 is a fragmentary side elevation of a winding machine of the type described with many of the parts broken away and those parts 40 which are not pertinent to the present invention being omitted for purposes of clarity;

Figure 2 is an enlarged fragmentary elevation with parts in section looking substantially along the line 2—2 in Figure 1 with many of the parts 45 broken away for purposes of clarity and showing the improved tail cutter in operating position;

Figure 3 is a fragmentary top plan view looking substantially at the top of Figure 2;

Figure 4 is a schematic fragmentary isometric view looking substantially in the direction of the arrow 4 in Figure 3 but showing the tail cutter in an inoperative position;

Figure 5 is a schematic fragmentary elevation

looking substantially along the line 5—5 in Figure 2;

Figure 6 is a schematic fragmentary elevation similar to Figure 5 but showing a modified form of blade for engaging and severing the tail of yarn.

Referring more specifically to the drawings, the numeral 10 broadly designates the framework of an automatic filling winding machine of a type such as is manufactured by Whitin Machine Works, Whitinsville, Mass., and which is generally known as a Whitin-Schweiter automatic filling bobbin winder. This framework 10 includes a casing 11 in which conventional gearing and cams, not shown, are disposed for effecting operation of the various conventional parts of the machine. The framework 10 also includes a horizontally disposed fixed rod 12 which extends outwardly from the front of the casing 11 and which has a conventional front stud plate 13 suitably secured thereto in which a conventional manually operable cam lever rod trigger 14 has pivotal movement.

This rod 12 usually supports a stationary bobbin holder, not shown in the present drawings, but which is clearly shown in a patent to W. Schweiter, No. 2,263,310 of December 30, 1941. The front stud plate 13 also has a shaft 15 extending rearwardly therefrom in parallel relation to the rod 12 which also assists in supporting the said stationary bobbin holder, not shown. A conventional rock shaft 16 is also supported at opposed ends thereof in the casing 11 and the front stud plate 13 and is instrumental in supporting and effecting operation of a conventional yarn feed carriage 20, portions of which are broken away and only those parts which are pertinent to the present invention being shown in Figure 1.

The conventional gearing, not shown, disposed within the casing 11 is instrumental in effecting intermittent rotation of a shaft 21 having a sprocket wheel 22 fixed thereon on which a conventional carriage operating chain 23 is mounted. Opposed ends of this chain 23 are connected to the front and rear ends of the carriage 20, as at 24 and 25 respectively. This chain also passes over a conventional roller 27 rotatably mounted, as at 30, on the stud plate 13. The automatic winding machine also includes a conventional spring loaded chuck member or bobbin head holder 32 which is moved into and out of operating position by conventional automatic means, not shown, disposed within the casing 11 and to which bobbins are directed, during a transfer operation, from a chute 33 suitably supported on the framework 10. There is only one bobbin shown in Figures 1, 2 and 3, this bobbin being designated at 34. The particular type of bobbin on which yarn is usually wound on machines of this type has an enlarged base 35 provided with a plurality of spaced peripherally disposed rings 36, these rings usually being made of metal and the bobbin base 35 usually being made of wood.

The conventional carriage 20 has a knock-off projection 40 integral therewith which, upon a desired amount of yarn being wound onto the bobbin 34, will engage a mating knock-off block 41 secured, as by a screw 42, on a conventional cam lever rod 43. This cam lever rod 43 is connected at its front end, in a conventional manner, intermediate the ends of the pivoted cam lever rod trigger 14. The rear end of the cam lever rod 43 is connected, as by a stud 44, to the

lower end of an arm 45 which extends upwardly, in Figures 1 and 2, and is fixedly mounted on the outer end of a conventional cam shaft 46 extending from the casing 11 at one side of the framework 10.

It is thus seen that, upon the knock-off projection 40 of the carriage 20 engaging the mating knock-off block 41, the block 41, along with the cam lever rod 43, will move from left to right in Figure 1 thus causing the arm 45 and the shaft 46 to move in a counter-clockwise direction. This will condition the conventional parts, not shown, of the machine within the casing 11 so as to cause the transfer of a bobbin from the bobbin holder 32 to be replaced by an empty bobbin in a conventional manner. This particular type of winding machine also includes a conventional shaft 47 having an arm 50 fixed thereon which is provided with a cam follower 51 in one end thereof for engaging a conventional back wind cam 52. There is also shown, in Figure 1, a conventional control knob 53 which is adapted to be manually positioned relative to a pin 54, and spaced below the control knob 53 is a picking finger unit 55. The parts 47 to 55 are shown merely to illustrate that these parts will not interfere with operation of the invention. The parts 47 to 55 are, otherwise, not pertinent to the present invention and a detailed description thereof is deemed unnecessary.

The parts heretofore described are conventional parts of an automatic filling bobbin winding machine and it is with these parts that the present invention is particularly adapted to be associated.

A tail cutter unit support 60 is suitably secured to the exterior surface of the front wall of the casing 11 by any suitable means such as screws 61. It might be stated that winding machines of this type are usually provided with suitable threaded bores for reception of the screws 61 so the improved tail cutter may be readily applied to the machine without altering the machine. This support 60 is provided with spaced bearing portions 62 and 63 in which a horizontally disposed, forwardly and rearwardly extending, shaft 64 is oscillatably mounted.

The medial portion of the shaft 64, between the bearing portions 62 and 63 of the support 60, has a tubular spacing member 65 adjustably secured thereon, as by a set screw 66. The front end of the shaft 64 extends forwardly of the bearing portion 63 and is fixedly mounted intermediate the ends of a first pivoted member or blade supporting member 67 which, as will be observed in Figures 2 and 4, extends inwardly and upwardly above the bobbin 34 positioned in the bobbin holder 32 and which has a forwardly bent substantially L-shaped portion 70 integral therewith which extends in substantially parallel relation to the axis of the bobbin holder 32. This forwardly bent portion 70 of the blade supporting member 67 extends downwardly and has a substantially rectangular blade 71 suitably secured thereto, as by screws 72.

This blade 71 is provided with a plurality of substantially semi-circular cavities or notches 73 in the lower or free edge thereof which, as may be observed in Figures 3 and 5, coincide with the rings 36 on the base 35 of the bobbin 34. These notches 73 define a plurality of spaced substantially flat-ended projections 74 which are adapted to enter the spaces between the rings 36 when the blade 71 is moved into

operative position, in a manner to be later described, the outermost of the projections 74 moving adjacent the outer or remote edges of the rings 36 in so doing.

The end of the blade supporting member 67, remote from the end to which the blade 71 is secured, has a horizontally bent tail portion or tab 75 integral therewith which is adapted to engage the lower end of an adjustment screw 76 when the blade 71 is moved into operative position as is clearly shown in Figure 2. This adjustment screw 76 threadably penetrates an outwardly projecting portion or ear 77 integral with the tail cutter unit support 60 and is locked in adjusted position by a lock nut 80 threadably mounted thereon. The support 60 has a horizontally disposed stub shaft 81 projecting outwardly therefrom on which a bell crank or second pivoted member, broadly designated at 82, is oscillatably mounted, this bell crank 82 being confined on the stub shaft 81 by a suitable washer 83 and a cotter pin 84.

The bell crank 82 has axially spaced outwardly extending first and second arms 85 and 86, respectively, which are spaced apart from each other by a suitable sleeve 87 to which they are suitably secured, the sleeve 87 being oscillatably mounted on the stub shaft 81. These arms 85 and 86 extend at substantially right angles with respect to each other.

The free end of the first arm 85 is resiliently connected to the portion of the blade supporting member 67, remote from the end to which the blade 71 is secured, by means of a coiled tension spring 90.

The tension spring 90 is connected to the free end of the first arm 85 by means of a suitable spring anchor 91 projecting inwardly from the free end of the arm 85 and the lower end of the tension spring 90 is connected to the tail or outer portion of the blade supporting member 67 by a suitable spring anchor 92 (Figures 2, 3 and 4). In order to insure that the blade 71 will be moved to substantially the inoperative position shown in Figures 1 and 4 when the arm 44 is disposed in substantially the position shown in Figure 1, a pin 93 is loosely confined within the coils of the tension spring 90 and, upon the free end of the first arm 85 being moved downwardly in Figure 2, the anchor 91 thereon will move the pin 93 against the anchor 92 on the blade supporting member 67 to cause the same to move in a counter-clockwise direction in Figure 2. The function of the tension spring 90 will be presently described.

Pivottally connected to the free or lower end of the second arm 86 of the bell crank 82, as at 95, is an irregularly bent link or connecting rod 96, this connecting rod 96 being connected to the lower or free end of the second arm 86 of the bell crank 82 by means of a cuff member 100 in which one end of the connecting rod or link 96 is threadably embedded and which is held in adjusted position therein by a lock nut 101 threadably mounted on the link 96 and bearing against the free end of the cuff member 100. This connecting rod or link 96 extends rearwardly and downwardly in a stepped manner so as to clear the parts 47 to 55 heretofore described and is pivotally mounted at its rear end on the stud 44 heretofore described (Figures 1 and 2).

The tubular spacing member 65 (Figure 3) is of less length than the distance between the bearing portions 62 and 63 so as to assist in obtaining an optimum adjustment of the position of the 75

blade 71 relative to the rings 36 on the base 35 of the bobbin 34. This spacing member 65 will also permit a relatively slight endwise movement of the shaft 64 so the projections 74 on the blade 71 may center themselves with respect to the spaces between the rings 36.

Referring to Figure 6, there will be observed a modified form of blade 101 which may be employed in lieu of the blade 71 heretofore described. This blade 101 is also adapted to be secured to the forwardly bent portion 78 of the blade support member 67 by any suitable means such as screws 102. It will be noted that this blade 101 differs materially from the blade 71 in that it is provided with a plurality of spaced flat bottom cavities 103, which are defined by a plurality of substantially V-shaped projections or prongs 104. These projections 104 function in the identical manner of the projections 74 on the blade 71.

Method of operation

It is well-known, to those familiar with the art, the manner in which bobbins, such as the bobbin 34, are fed to the chuck or bobbin holder 32 as preceding bobbins are transferred automatically through conventional means associated with this machine and as a new bobbin is positioned in engagement with the bobbin holder 32 as shown in Figures 1, 2, 3 and 4, the bobbin holder or chuck 32 partially recedes into the casing 11 and as the new bobbin is positioned in alignment with the same, the tail portion of the yarn, which is indicated at T in Figures 3 and 4, is clampingly held between the bobbin holder 32 and the base 35 of the bobbin. The carriage 20 then directs the yarn to the bobbin in a conventional manner and, in so doing, the tail portion T of the yarn is pulled tightly across the outer edges of the peripherally disposed rings 36 on the base of the bobbin 34 as is clearly shown in Figures 3 and 4.

The chain 23 then functions in a well known manner to gradually move the carriage 20 from left to right in Figure 1 until the bobbin is filled with yarn and, at which time, the projection 40 on the carriage will engage the mating knock-off block 41 on the cam lever rod 43 and will cause the cam lever rod 43 to move from left to right in Figure 1. This will, in turn, cause the arm 45 to rotate a partial revolution in a counter-clockwise direction to impart movement to the link 96 from left to right in Figure 1.

This will cause the bell crank 82 to move in a counter-clockwise direction in Figure 1, with the result that the first arm 85 will move upwardly in Figures 1 and 2. This will cause the blade supporting member 67 to move in a clockwise direction from the position shown in Figure 4 to the position shown in Figure 3, that is, until the tab portion 75 of the blade supporting member 67 engages the lower end of the adjustment screw 76. This adjustment screw 76 will have been adjusted in such a manner that, upon the tab 75 of the blade supporting arm 67 engaging the adjustment screw 76, the walls of the notches 73, in Figure 5, will assume a position in precise closely spaced relation to the outer peripheral edges of the rings 36. The space between the outer edges of the rings 36 and the walls of the notches 73 may thus be determined within a few thousandths of an inch as desired.

The notches 73 are of such depth that the lower edges of the projections 74 on the blade 71 in Figure 5 will assume a position in precise closely spaced relation to the periphery of the base 35 of the bobbin 34. Thus, the clearance

between the edges of the projections 14 and the base 35 of the bobbin 34 and the clearance between the rings 36 and the walls of the notches 73 is less than the diameter of the yarn and the tail of the yarn T, which extends across the outer edges of the rings 36, will, due to rotation of the bobbin 34, engage the projections 14 on the blade 71 to be severed thereby, in which instance, the projections will either cut or break the tail of yarn immediately adjacent the point at which the yarn is initially wound onto the bobbin 34.

It might be stated that, if so desired, an operator may cause the bobbin 34 to transfer before it is filled by grasping the manually operable cam rod trigger lever 14 and moving the same from left to right in Figure 1, which will, in turn, move the cam lever rod 43 from left to right to also impart movement of the tail cutter blade 71 into operative position.

Whether the device is operated manually or automatically, as heretofore described, the arm 45 may continue its movement in a counter-clockwise direction in Figure 1 after the portion 75 of the blade supporting member 67 has engaged the lower end of the adjustment screw 76 and, therefore, the tension spring 90 is provided to permit the bell crank 82 to continue its movement in a counter-clockwise direction in Figure 1 after the blade 71 has assumed the desired operative position. The blade 71 is moved into operative position only momentarily and conventional means disposed within the casing 11 of the framework 10 will cause the shaft 46, along with its arm 45, to move a partial revolution in a clockwise direction in Figure 1 to thus return the associated parts to inoperative position.

In this instance, the bell crank 82 is moved in a clockwise direction, in Figure 1, causing its first arm 85 to move downwardly in Figure 4 until its spring anchor 91 engages the upper end of the pin 93, the lower end of the pin 93 normally resting upon the spring anchor 92 of the blade supporting arm 67. Upon the spring anchor 91 being moved into engagement with the pin 93, it is evident that continued downward movement of the arm 86 will cause the blade supporting member 67 to move in a counter-clockwise direction, in Figure 3 until it assumes substantially the position shown in Figures 1 and 4. A transfer operation then takes place, that is, the bobbin on which the yarn has been wound is discharged from the bobbin holder 32 and an empty bobbin replaces the same, and the cycle in the operation of the device is repeated as heretofore described.

The modified form of blade 101 functions in the identical manner in which the blade 71 functions upon being moved into and out of operating position and a further description thereof is unnecessary.

In the drawings and specification, there has been set forth a preferred embodiment of the invention and although specific terms are employed, they are used in a generic and descriptive sense only, and not for purposes of limitation, the scope of the invention being defined in the claims.

I claim:

1. An improvement in a winding machine for winding yarn onto a bobbin provided with a base having a plurality of spaced peripherally disposed rings thereon, said winding machine having means for receiving the bobbin and for imparting rotation thereto and also having means for

5 directing the yarn to the bobbin and also having means for clampingly holding the tail of the yarn during a winding operation and whereby the yarn will extend across the outer periphery of said rings as it is being wound on said bobbin, said machine also having a pivoted arm extending from one side thereof and also having means automatically operable upon a predetermined amount of yarn being deposited on a bobbin for moving the pivoted arm in one direction and then returning the arm to its original position, said improvement comprising a blade supporting member pivoted intermediate its ends to the framework of the winder, a blade secured to one end of said pivoted member and normally disposed in an inoperative position relative to the base of the bobbin during a winding operation, means automatically operable upon a desired amount of yarn being wound onto said bobbin for moving the pivoted member to cause the blade to move into operative position, said blade being provided with a plurality of closely spaced substantially semi-circular cavities in its end adjacent the bobbin, said cavities defining 15 a plurality of spaced projections, means limiting movement of the pivoted member upon the blade moving into operative position so the projections will enter the spaces between the rings and said cavities being of such depth that the walls of the cavities will be disposed in precise closely spaced relation to the outer periphery of said rings and the outer edges of the projections will be disposed in closely spaced relation to the periphery of the base of the bobbin for entering 20 the path of the tail of yarn extending across the rings so as to cause a severance of said tail of yarn, a mechanical connection between the blade supporting member and the pivoted arm extending from the side of the machine and a resilient means interposed in the mechanical connection to permit movement of the pivoted arm on the side of the machine and its corresponding mechanical connection beyond the limited movement of the pivoted member.

2. An improvement in a winding machine provided with means for successively receiving and transferring the bases of bobbins, each having a plurality of spaced peripherally disposed rings on its base, said winding machine having a framework and also having means for imparting rotation to the bobbin, and also having means for directing yarn to the bobbin and also having means for clamping the yarn at the base of the bobbin as the yarn is initially fed to the bobbin so the tail of the yarn extends across said rings and said framework also having a shaft extending from one side thereof and also having an arm extending radially from said shaft and also having means automatically operable upon a transfer operation taking place for moving said arm about the axis of said shaft, said improvement comprising a blade supporting member pivoted intermediate its ends on the framework, a blade secured to one end of said blade supporting member and having a plurality of closely spaced projections on its free end, said projections being spaced substantially parallel to the axis of a bobbin on which yarn is being wound, a bell crank pivoted on said framework and having a pair of radially extending arms thereon, a resilient connection between one of the arms of said bell crank and the end of the blade supporting member remote from the blade, a link pivotally connected at one end thereof to the other arm of the bell crank and

pivotedly connected at the other end thereof to said arm extending from the shaft at the side of the framework and means limiting movement of said blade supporting member whereby, upon a predetermined amount of yarn being deposited on the bobbin, the arm extending from the shaft will impart movement in one direction to the bell crank to, in turn, impart movement to the blade supporting member to cause the projections on said blade to move into the spaces between the rings on the bobbin and whereby the projections will come to rest in closely spaced relation to the periphery of the base of the bobbin between said rings and in the path of the tail of yarn extending thereacross so as to cause a severance of the tail and the resilient connection serving to permit movement of the bell crank in a given direction after the blade supporting member has ceased its movement.

3. An improvement in a winding machine provided with means for successively receiving and transferring the bases of bobbins, each having a plurality of spaced peripherally disposed rings on its base, said winding machine also having a framework and also having means for imparting rotation to the bobbin, and also having means for directing yarn to the bobbin and also having means for clamping the yarn at the base of the bobbin as the yarn is initially fed to the bobbin so the tail of the yarn extends across said rings and said framework also having a shaft extending from one side thereof and also having an arm extending radially from said shaft and also having means automatically operable upon a transfer operation taking place for oscillating said arm about the axis of said shaft, said improvement comprising a blade supporting member pivoted intermediate its ends on the framework, a blade secured to one end of said blade supporting member and having a plurality of closely spaced projections on its free end, said projections being spaced substantially parallel to the axis of a bobbin on which yarn is being wound, a bell crank pivoted on said framework and having first and second radially extending arms thereon, a resilient connection between the first of the arms of said bell crank and the end of the blade supporting member remote from the blade, a link pivotedly connected at one end thereof to the second arm of the bell crank and pivotedly connected at the other end thereof to said arm extending from the shaft at the side of the framework and means limiting movement of said blade supporting member whereby, upon a predetermined amount of yarn being deposited on the bobbin, the arm extending from the shaft will impart movement in one direction to the bell crank to, in turn, impart movement to the blade supporting member to cause the projections on said blade to move into the spaces between the rings on the bobbin and whereby the projections will come to rest in closely spaced relation to the periphery of the base of the bobbin between said rings and in the path of the tail of yarn extending thereacross so as to cause a severance of the tail and the resilient connection serving to permit movement of the bell crank in a same direction after the blade supporting member has ceased its movement, the resilient connection including a coiled tension spring connected at one end thereof to the first arm of the bell crank and connected at its other end to the end of the blade supporting member remote from the end to which the blade is secured, a pin disposed within the confines of the

tension spring and opposed ends thereof normally engaging the bell crank and the blade supporting member so as to permit the bell crank to continue its movement in said same direction after the blade supporting member has ceased its movement and to permit the bell crank to move the blade supporting member to inoperative position upon movement of the arm extending from its said shaft at the side of the framework in the opposite direction.

4. In a winding machine for winding yarn on bobbins having a base provided with a plurality of spaced rings encircling the base of the bobbins and across which the tail of the yarn is passed at the beginning of the winding operation whereby the tail of the yarn rotates with the bobbin, said machine also having a pivoted arm extending from one side thereof and means automatically operable upon a predetermined amount of yarn being deposited on a bobbin for moving the pivoted arm in one direction and then returning the arm to its original position; the combination of movable means mounted adjacent the base of the bobbin and having a plurality of projections thereon adapted to pass between said rings simultaneously, said movable means normally occupying an inoperative position relative to the base of the bobbin during a winding operation, mechanical connections between said movable means and said pivoted arm whereby said pivoted arm will move the projections on said movable means between the rings simultaneously and into the path of the tail of yarn to break the same upon the completion of winding of yarn on a bobbin and then return said movable means to its normal position, and a resilient means interposed in said mechanical connections to permit movement of the pivoted arm and its corresponding connections after the projections on the movable means have passed between said rings.

5. In a winding machine for winding yarn onto a bobbin having a plurality of spaced peripherally disposed rings thereon said machine having means for receiving the bobbins, one at a time, and for imparting rotation thereto, means for directing the yarn to the bobbin, means for clampingly holding the tail of yarn during the winding operation whereby the yarn will extend across the outer periphery of said rings as it is being wound on said bobbin, said machine also having a first pivoted arm extending from one side thereof and means automatically operable upon a predetermined amount of yarn being deposited on a bobbin for moving the pivoted arm in one direction and then returning the arm to its original position; the combination of a blade supporting member pivoted intermediate its ends to the framework of the winder, a blade fixed to one end of said blade supporting member and normally disposed in an inoperative position relative to the base of the bobbin during a winding operation, a second pivoted arm spaced from the blade supporting member, a mechanical connection between the second pivoted arm and the first pivoted arm extending from one side of the machine, a resilient means connecting the second pivoted arm to the blade supporting member and being relaxed while the blade is in said normally inoperative position whereby said blade will be resiliently moved into operative position relative to the rings on the bobbin for ensnaring and causing a severance of said tail of yarn upon movement of said first pivoted arm in said one direction.

6. In a structure according to claim 5, said

blade having a plurality of closely spaced projections on its end adjacent the bobbin and being so arranged as to enter the spaces between the rings when moved to operative position, and means limiting movement of said blade toward operative position whereby said resilient means permits movement of the first pivoted arm on the side of the machine and its corresponding mechanical connections beyond the limited movement of the blade supporting member.

7. In a winding machine provided with means for successively receiving and transferring the bases of bobbins, each having a plurality of spaced peripherally disposed rings on its base, said winding machine having a framework, means for imparting rotation to the bobbin, means for directing yarn to the bobbin, means for clamping the yarn at the base of the bobbin as the yarn is initially fed thereto so the tail of yarn extends across said rings, a shaft extending from one side of said framework, an arm extending radially from said shaft and means operable automatically upon the occurrence of a transfer operation for oscillatably moving said arm about the axis of said shaft; the combination of a blade supporting member pivoted intermediate its ends on said framework, a blade fixed to one end of said blade supporting member and having a plurality of closely spaced projections on its free end, said projections being spaced substantially parallel to the axis of a bobbin on which yarn is being wound, a lever pivoted on said framework, a resilient connection between the lever and the end of the blade supporting member remote from the blade, a link connection between said lever and said arm extending from the shaft at the side of the framework, adjustable limiting means limiting movement of said blade supporting member whereby,

during a transfer operation the arm at the side of the framework will impart movement in one direction to said lever and the blade supporting member to cause the projections on said blade to move into predetermined closely spaced relation to the base of the bobbin and between said rings so as to cause a severance of the tail of the yarn extending across the rings, and the resilient connection serving to permit movement of the lever in a given direction after the blade supporting member has ceased its movement as limited by said limiting means.

8. In a structure according to claim 7, said resilient connection including a coiled tension spring connected at one end thereof to said lever and connected at its other end to the end of the blade supporting member remote from the end to which the blade is fixed, a pin disposed within the confines of the tension spring and opposed ends thereof normally engaging the lever and the blade supporting member so as to permit the lever to continue its movement in said given direction after the blade supporting member has ceased its movement and whereby said lever will move the blade supporting member to inoperative position upon movement of the arm at the side of the framework in the opposite direction.
